WILLIAM H. EDSALL AND FRANK LA OTIS LATHROP, OF WALLINGFORD, CONNECTICUT,
ASSIGNORS TO H. L. JUDD COMPANY, OF WALLINGFORD, CONNECTICUT, A CORPOR-
ATION OF NEW YORK.

DRAPERY-CARRIER.

1,329,889.

Specification of Letters Patent.

Patented Feb. 3, 1920.

Application filed August 5, 1919. Serial No. 315,424.

To all whom it may concern:

Be it known that we, WILLIAM H. EDSALL and FRANK LA OTIS LATHROP, citizens of the United States of America, residing at Wallingford, Connecticut, have invented a new and useful Drapery-Carrier, of which the following is a specification.

This invention relates to that type of a device known as a curtain support and it is particularly designed with reference to providing a main rod supporting element slotted and provided with interior tracks for supporting a series of carriers which may be slid to and fro on said tracks in such a manner that when a curtain or other drapery is secured to said carriers the said drapery may be adjusted as desired with relation to the passageway or window in which it is located. Supports of this general type have long been known and used and have customarily been made of sheet metal. Obviously when the carriers are made of sheet metal there is danger that if the same are tilted the edge of one carrier may over-ride the edge of an adjacent carrier and become jammed in the guide-way or slot especially if the tracks have been deflected or badly worn.

It is the chief object of our invention to provide simple and effective means which do not add materially to the cost of production, the function of which is to prevent the aforesaid over-riding and jamming of said carriers. Further, our improved construction guarantees the free sliding of said carriers.

In carrying out our invention, we provide the carrier disks with stop shoulders or lugs at their opposite ends, which shoulders form abutments serving to prevent the carriers from riding upon one another. In the preferred form, the rod is provided along its opposite edges with downwardly and inwardly turned flanges forming spaced interior tracks for supporting the carriers. The upper wall of the rod is preferably corrugated longitudinally to stiffen the same and to provide a central channel directly above the slot. These corrugations also form ribs above the tracks the same being spaced apart therefrom only slightly more than the thickness of the carrier. By this form of construction relatively narrow upper and lower bearing tracks are provided affording

a minimum of resistance to the sliding of the carriers.

Figure 1 is a cross sectional view illustrating a preferred form of our invention.

Fig. 2 is a longitudinal view thereof.

Fig. 3 is a perspective view of a single carrier or slide.

Fig. 4 is an end view thereof.

Fig. 5 is a cross section of a modification.

Fig. 6 is a view of the underside of the slide shown in Fig. 5.

Fig. 7 is a cross sectional view of a modified form of the slide.

Describing first the construction shown in Figs. 1 to 4 inclusive, it will be seen that the main supporting rod is corrugated longitudinally and the opposite edges thereof are turned downwardly and inwardly so as to form two spaced supporting flanges 1-1. Each carrier comprises a disk-like member 2 of a size adapted to slide within the supporting rod and upon the guide-ways or flanges 1-1. Each end of each carrier disk 2 is provided with a stop shoulder 3 which is offset in such a manner as to form an abutment so that two adjacent carriers when brought into contact are prevented from over-riding one another in the slotted portion of the rod and becoming jammed therein. Any suitable attaching means such as an eye 4 may be secured to each carrier from which the curtain or drapery may be suspended.

In Fig. 2 we have shown two adjacent carriers, one being in an extremely tilted position in the slotted rod, and in this same view we have illustrated one of the side flanges or tracks as being sagged, thereby inviting the over-riding and jamming of the carriers, yet it will be seen by reference to this figure, that the stop shoulders operate to effectively prevent said over-riding of said pieces even under these most unusual conditions.

In Fig. 1, it will be seen that the inturned flanges 1-1 are preferably curled up somewhat so as to provide a line support for the carrier. The corrugations in the top of the rod likewise form comparatively narrow top guides or beads 5-5 upon which the upper surface of the carrier may freely run in the event the same is tilted by a strain on the drapery in the act of shifting the same.

The vertical clearance space for the car-

rier within the rod is preferably only a little greater than the thickness of the carrier yet sufficient to permit said carriers to move with entire freedom and to tilt somewhat.

5. In the modified form shown in Fig. 5, we have shown the main supporting rod as corrugated in such a manner as to provide a relatively deep center longitudinal channel 6, and in this case we have provided the 10 carrier with lugs not only at the ends but at the side edges, the end lugs being shown at 3—3, the side lugs being indicated at 7—7 and located directly above the inwardly curled flanges or tracks 1—1.

15. In the modified form shown in Fig. 7 the rod may correspond in cross section to that shown in Fig. 5 in which the deep central channel 6 is provided and the carriers may be provided with upwardly projecting stop 20 shoulders or lugs 3^a at their ends instead of the downwardly projecting shoulders 3 such as shown in the Figs. 1 to 4. The deep central channel in the supporting rod furnishes ample room for such lugs 3^a as well as room 25 for the nail or screw heads by which the rods are secured to an overhead support such as the top of a door or window casing.

It should be understood that the stop lugs at the ends of the carriers may be formed 30 in any desired manner, but in the preferred form they are integrally formed with the carrier by bending the edges of the metal, which process is extremely simple and cheap and adds comparatively little to the cost of 35 production. So also the outline of the blank from which the carrier is formed may be modified at will, that is to say, it may be round or slightly oval as indicated in Figs. 1 to 4, or it may be substantially rectangular as indicated in Figs. 5 and 6, or it may 40 be given any shape which will lend itself to the forming of appropriate stop lugs or shoulders.

It should be understood also that we have 45 shown only preferable constructions of our invention.

We claim:

1. A drapery carrier comprising, a rod having inwardly facing flanges with grooves 50 above the flanges, carrier disks resting on said flanges and slidably in said grooves, said disks having vertically disposed flanges at opposite ends to prevent adjacent ends of adjacent carriers from overlapping.

55. 2. A drapery carrier comprising, a supporting member having oppositely disposed spaced flanges with grooves above the flanges, carrier members slidable in said grooves on said flanges and having downwardly extending stop flanges at opposite 60 ends between the supporting flanges to prevent adjacent carrier members from riding on one another.

3. A drapery carrier comprising, a sheet 65 metal support having inwardly and up-

wardly turned spaced flanges and providing oppositely disposed grooves and having a centrally located downwardly facing groove above the opening between said flanges, the upper wall of said support providing longitudinally 70 extending relatively narrow upper bearing tracks above said flanges and a series of carriers slidably mounted on said flanges in said grooves, each carrier being provided with stop shoulders at its opposite 75 ends to prevent adjacent ends of adjacent carriers from passing each other.

4. A drapery carrier comprising, a sheet metal supporting member provided with inwardly and upwardly directed spaced flanges 80 forming relatively shallow grooves facing toward the center and a series of flat carrier members slidably supported on the edges of said flanges in said grooves, each carrier member having stop shoulders on its opposite 85 site ends between said flanges.

5. A drapery carrier comprising, a rod having inwardly facing flanges with shallow grooves above the flanges, flat carrier members resting on said flanges and 90 slidably in said grooves, said carrier members having vertically disposed stop shoulders at opposite ends to prevent adjacent ends of adjacent carriers from overlapping.

6. A drapery carrier comprising, a supporting member having oppositely disposed spaced flanges with shallow grooves above the flanges, flat carrier members slidable in 95 said grooves on said flanges and having downwardly extending stop shoulders at opposite 100 ends between the supporting flanges to prevent adjacent carrier members from riding on one another.

7. A drapery carrier comprising, a sheet metal support having inwardly turned flanges and providing oppositely disposed shallow grooves and having a centrally located downwardly facing groove above the opening between said flanges, the upper wall of said support providing longitudinally extending, relatively narrow upper bearing tracks above said flanges and a series of carriers slidably mounted on said flanges in 110 said grooves, each carrier being provided with stop shoulders at its opposite ends to 115 prevent adjacent ends of adjacent carriers from passing each other.

8. A drapery carrier comprising, a rod having inwardly facing flanges with shallow grooves above the flanges and relatively flat carrier disks having their edges resting on the flanges in said grooves and having stop shoulders on their opposite ends between 120 said flanges.

9. A drapery carrier comprising, a rod 125 having oppositely disposed flanges providing edge-like bearing tracks, relatively flat disk-like carriers having their edges slidably supported on said flanges, the upper wall of said rod being provided with relatively nar-

row bearing tracks spaced apart in a plane above the edges of said flanges a distance but slightly greater than the thickness of said carriers, said carriers being provided 5 with stop shoulders on their opposite ends to prevent the adjacent end of adjacent carriers from overriding.

10. A drapery carrier comprising a rod having a longitudinally corrugated upper 10 surface forming a plurality of downwardly extending ribs forming narrow top guides, downwardly extending flanges at the opposite edges of said top portion, the lower edges of said flanges being turned inwardly to form 15 carrier supporting tracks spaced apart by a longitudinal slot, a plurality of carriers slidably mounted in the space within said rod with means on said carriers for securing 20 drapery thereto, the space between said tracks and said top guide ribs being only slightly greater than the thickness of that part of said carriers located therebetween.

11. A drapery carrier comprising a rod having a longitudinally corrugated upper 25 surface forming a plurality of downwardly extending ribs forming narrow top guides, downwardly extending flanges at the opposite edges of said top portion, the lower edges of said flanges being turned inwardly 30 to form carrier supporting tracks spaced apart by a longitudinal slot, a plurality of carriers slidably mounted in the space within said rod with means on said carriers for

securing drapery thereto, the space between said tracks and said top guide ribs being 35 only slightly greater than the thickness of that part of said carriers located therebetween, with stops on the ends of said carriers.

12. A drapery carrier comprising, a rod 40 having inwardly turned flanges with shallow grooves above them and a plurality of sliding members each having integral lugs guided in said grooves and integral stop shoulders on their opposite ends, and means 45 for securing drapery to said sliding members.

13. As an article of manufacture, a slide for a drapery carrier comprising, a relatively flat disk having its opposite edges 50 adapted to slide in a groove of a supporting rod and having vertically disposed integral stop shoulders on opposite ends to prevent adjacent disks from overlapping when in the rod, and means for securing drapery to 55 said disk.

14. As an article of manufacture, a slide for a drapery carrier comprising, a relatively flat disk having integral lugs on its opposite sides adapted to be guided in the 60 grooves of a rod and having vertically disposed integral stop shoulders on its opposite ends, and means for securing said drapery to said disk.

WILLIAM H. EDSALL.
FRANK LA OTIS LATHROP.
